FIG.5.

UNITED STATES PATENT OFFICE.

FRANK R. PARSONS, OF PROVIDENCE, RHODE ISLAND.

INKSTAND.

SPECIFICATION forming part of Letters Patent No. 393,026, dated November 20, 1888.

Application filed April 28, 1888. Serial No. 272,193. (No model.)

To all whom it may concern:

Be it known that I, FRANK R. PARSONS, of the city and county of Providence, and State of Rhode Island, have invented a new and 5 useful Improvement in Inkstands; and I do hereby declare the following specification, taken in connection with the accompanying drawings, forming a part of the same, to be a description thereof.

10 This invention relates to that variety of inkstands in which the hinged cover has connected therewith a weight for normally holding the cover raised and arms or members for receiving a pen-holder, which when placed 15 thereon will close the cover and retain it in a closed position.

The invention consists in certain features of construction and arrangement, hereinafter described and claimed.

20 Referring to the drawings, Figure 1 represents a side view of an inkstand embodying the invention. Fig. 2 shows a top view of the same. Figs. 3, 4, and 5 are detail views showing forms of pivotal bearings that may be used 25 on the cover member and the standards, the standards being represented in vertical section.

A is the base of the inkstand, which base may be of any preferred form or design.

30 B B are standards secured thereto and projecting upwardly therefrom, upon which the cover member C is mounted to swing in a vertical plane. The standards are furnished at their upper ends with bearings b b, for receiving the pintles c c on the cover member. This member is composed, in the main, of a cover portion, d, adapted to fit closely upon the top of the inkstand proper, D, two arms, e e, and a weight, f. The arms e e are shown as connected to the cover d by a bar, g, and they may be connected, also, by two braces, h h, and the weight is shown as connected to said bar by a curved arm, i. The pintles c c project from the outer sides of the arms e e or 40 from the end of the bar g. The parts composing the cover member C are preferably cast integral with one another or made of one piece of metal, thereby avoiding the use of solder, screws, or rivets in securing them together. The arms e e are provided near their 45 free ends with cavities k k, for receiving a pen-holder, L, and just in the rear of said cavities

the arms are preferably furnished with upwardly-projecting fingers m m, respectively, which serve as guides against which the pen-holder can be placed when it is to be put into the cavities k, less care being required in locating the holder in the cavities than would be necessary were no fingers employed. The base A is also preferably provided with ears 55 a a to hold an extra pen-holder or a pencil.

The weight f is intended to be sufficiently in excess of the weight of the front portion of the cover member or that portion forward of an axial line passing through the pivots c c to 65 cause the cover member to tilt or swing, as shown by dotted lines in Fig. 1, when the pen-holder is removed, so that ink may be obtained from the stand D. As defects in the cover member, as a casting, are liable to vary 70 its proper balance, I preferably constructs said member with a cavity, n, Fig. 1, in the cover d, to receive a supplemental weight of lead or other material, and the weight f may also have a cavity, n, for the same purpose, so that the 75 proper balance of the cover member on its pintles can be easily and accurately secured.

As the cover is intended to be closed by the weight of a pen-holder, it is desirable there shall be the least possible friction between the 80 pintles c c and bearings b b. I prefer, therefore, to bevel the pintles to an edge, c', on the under side and to bevel the bearings b b to an edge, b', as shown in Figs. 1 and 3. With this construction the pintles and bearings will engage at 85 but a single point, thereby enabling the cover member to tilt very easily, and preventing dust from interfering with its movements, as well as dispensing with the use of a lubricant. Instead of beveling the bearings b b as just 90 described, however, the same result may be secured by inclining the edge c' on the pintles, as shown in Fig. 4, so that the pintles will only bear on the edge b' of the bearings; or the edge c' may be inclined and the bearing 95 b beveled, as shown in Fig. 5.

What I claim, and desire to secure by Letters Patent, is—

1. The combination, with the base provided with standards B B, having bearings b b, and an 100 inkstand located on said base, of a tilting cover member, C, having pivots c c and composed of a cover portion, d, arms e e, having cavities k k, for receiving a pen-holder, and a

weight, *f*, the said cover member being furnished with a cavity or cavities, *n*, for receiving a supplemental weight, substantially as set forth.

5 2. The combination, with the base provided with standards *B B*, having bearings *b b*, and an inkstand located on said base, of a tilting cover member, *C*, having pivots *c c* and composed of a cover portion, *d*, arms *e e*, having 10 cavities *k k*, for receiving a pen-holder, and having upwardly-projecting fingers *m m*, and a weight, *f*, the parts of said cover member all being integral or cast in one piece, substantially as set forth.

3. The combination, with the base provided with standards *B B*, having bearings *b b*, and an inkstand located in said base, of a tilting cover member, *C*, having pivots *c c* and composed of a cover portion, *d*, arms *e e*, having cavities *k k*, for receiving a pen-holder, and a 20 weight, *f*, the engaging portions of the pivots *c c* and bearings *b b* being brought to an edge, as described, substantially as and for the purposes specified.

FRANK R. PARSONS.
